UNITED STATES PATENT OFFICE.

JOSEPH FENNELL, OF CYNTHIANA, KENTUCKY.

IMPROVEMENT IN BOOTS FOR HORSES.

Specification forming part of Letters Patent No. 133,768, dated December 10, 1872.

To all whom it may concern:

Be it known that I, JOSEPH FENNELL, of Cynthiana, in the county of Harrison and State of Kentucky, have invented a new and useful Improvement in Pastern-Joint and Fetlock Boot for Horses, of which the following is a specification:

The object of this invention is to provide convenient and efficient means for preventing "interference" in horses, or to prevent ill-consequences when interference or over-reaching occurs; and it consists in a boot constructed in two parts, connected together by a flexible ligature, and arranged as hereinafter described.

In the drawing, Figure 1 represents the boot applied to the horse's leg, as when in use; Fig. 2 is a back view, and Fig. 3 an inside view, of the boot.

Similar letters of reference indicate corresponding parts.

A is the part of the boot for protecting the first or pastern joint of the horse's leg. It is formed of leather and cloth stitched together with suitable straps B B and buckle for fastening it around the leg, above the joint, as represented in Fig. 1. The leather, or outside portion, is curved or made somewhat concave on the inside so as to fit the joint. The inside cloth lining is stitched tightly thereto, and there is a stuffing of wool between, making thereby a soft and flexible pad fastened by the straps on the outside of the leg, as seen in Fig. 1. C represents the

lower portion of the boot, constructed of one or more thicknesses of leather and lined with chamois-skin or other soft material. D D are the straps by which it is fastened to the fetlock. The upper and lower portion are united by the flexible connection E, so that the lateral action of each is free while both are secured to the horse's limb. This lower portion of the boot, in order to fit the place intended, is made somewhat convex on the inside, or is curved from end to end vertically, as indicated in the drawing. With the boot thus attached the horse cannot injure himself when going at a high rate of speed by overreaching or interfering, and its advantages will be at once understood and appreciated by sporting men and all who are interested in the management of horses.

While the boot fits snugly, it will at the same time allow all sand, dirt, and other like matters which may work in to discharge freely.

Having thus described my invention, I claim as new and desire to secure by Letters Patent—

A boot for the pastern-joint and fetlock of horses, constructed in two parts, A. and C, united by the ligature E, substantially as shown and described.

JOSEPH FENNELL.
